COMBINED ICE SCRAPER AND OVERCAP

Laurel E. Carr, Chicago, Ill., assignor to The Bell Company, Inc., Chicago, Ill.

Filed Sept. 18, 1972, Ser. No. 289,808

Term of patent 14 years

Int. Cl. D9—07

U.S. Cl. D9—261

FIG. 1.

FIG. 2.

FIG. 3.

FIG. 4.

FIG. 5.

FIG. 6.

FIG. 7.

FIG. 1 is a rear elevational view of a combined ice scraper and overcap showing my new design;

FIG. 2 is a left side elevational view;

FIG. 3 is a front elevational view;

FIG. 4 is a top plan view;

FIG. 5 is a bottom plan view;

FIG. 6 is a perspective view; and

FIG. 7 is an enlarged scale fragmentary view of the breaker points.

I claim:

The ornamental design for a combined ice scraper and overcap, substantially as shown and described.
